UNITED STATES PATENT OFFICE.

JOSEPH BRAKELEY, OF NEW YORK, N. Y.

MACHINE FOR PLANING BARK.

Specification of Letters Patent No. 31,697, dated March 19, 1861.

To all whom it may concern:

Be it known that I, JOSEPH BRAKELEY, of the city, county, and State of New York, have invented a new and Improved Machine 5 for Cutting Bark for the Use of Tanners; and I do hereby declare that the following is a full, clear, and exact description of the same, reference being had to the annexed drawings, making a part of this specification, in which—

Figure 1, is a side sectional view of my invention taken in the line $x-x$ Fig. 2. Fig. 2, a transverse vertical section of the same, taken in the line $y-y$, Fig. 1, and looking in 15 the direction indicated by the arrows.

Similar letters of reference indicate corresponding parts in the two figures.

To enable those skilled in the art to fully understand and construct my invention I 20 will proceed to describe it.

A represents an oblong rectangular box, which is formed of two longitudinal parts a, b , connected together by parallel bars B, which are secured to the parts a, b , by pivots 25 c . This manner of attaching the parts a, b , together admits of the upper part a , being adjusted higher or lower so as to be nearer to or farther from the part b , and one of the bars B, is longer than the others in order to 30 serve as a handle, as shown at B', said handle having a hole in it to fit on either of a series of pins d , and secure the part a , in the desired position, see Fig. 1.

In the upper part a , of the box A, there is 35 placed a cylinder C, which has a series of knives e , attached to its periphery. These knives extend the whole length of cylinder C, and they have a tangential position relatively with the periphery of the cylinder as 40 shown in Fig. 1.

Within the part a , of the box A, there is placed a horizontal bed D, which rests on parallel bars f , the lower ends of which are attached by pivots to the part a . One of the 45 bars f' , is longer than the others to serve as a handle and it has a hole made in it to fit over any of a series of pins g , to secure the bed D in the desired position relatively with cylinder C, according to the depth of cut 50 required.

In the part b , of the box A, there is placed a cylinder E, the axis of which is about in a horizontal plane with the axis of the cylinder C, as shown in Fig. 1. To admit of 55 this the end of the part b , containing cylinder E, extends upward and fits in a concave

in the under side of part a . The cylinder E, is provided with knives h , similar to those of cylinder C, and within the part a , there is placed a horizontal bed F, which bed is 60 between the two cylinders C, E, as shown clearly in Fig. 1, the bed F, being on a line with the edges of the knives e , of cylinder C.

G, G, are fluted pressure rollers, the axes of which are placed in the ends of arms H. 65 These arms H, are placed on a shaft I, and they have springs i , connected to them. To one end of the axes of the rollers G, pulleys J, are attached, and to one end of the axes of the cylinders C, E, there are attached pulleys j . Suitable belts pass around the pulleys above named to communicate motion to them. 70

The operation is as follows: The bark to be cut is placed one slab at a time on the bed D, the "ross" or outer side being upward, and motion is given the cylinders and rollers by any convenient power, the cylinders and rollers rotating in the direction indicated by the arrows in Fig. 1. The inner part k , of the bark is cut by the cylinder C, the cut portion passing down from the machine as shown in Fig. 1. The depth of this cut is regulated according to the thickness of part k , by adjusting the bed D. 85 The rollers G, G, feed the bark along and the bark passes from bed D, to the bed F, the difference in height between the two beds being equal to the depth of the cut of the knives e . The bark then in passing over 90 the cylinder E, has its second part or portion l , cut from it, said part being discharged from the machine as shown in Fig. 1. The remaining outside layer technically termed the "ross" and designated by m , is 95 discharged at the end of the machine, as also shown in Fig. 1. The depth of the cut of cylinder E, is regulated according to the thickness of the part l , of the bark by adjusting the whole of the part a , of the box A, 100 through the medium of the bars B. This adjustment of part a , of course admits of the regulating of the bed F, relatively with the cylinder E, while the relative position of the cylinder C, with its bed D, is not affected 105 thereby.

The bed D, it will be observed is hung upon arms f , whose axes and length are so arranged and proportioned that the inner edge or extremity of the said bed, will, when 110 said bed is adjusted, move on a concentric or circular line, corresponding with the

periphery of the cylinder C. Thus the proper relative distance or throat space between the cutters of cylinder C, and the beds D is maintained whatever may be the adjustment of the said bed. The bed F has a similar concentric adjustment in respect to the cylinder E.

This machine admits of a very ready adjustment of the beds to suit the thickness of the two parts of the bark, and said parts may be not only kept separate but also divided with the greatest nicety the latter result being due to the manner in which the beds are adjusted. This is an important feature for the inner part *k*, is far more valuable than the part *l*, for tanning while the "ross" is comparatively worthless.

Having thus described my invention what I claim as new and desire to secure by Letters Patent, is,

1. The combination with each other and with the feed rollers G, G, of the adjustable beds D, F, and cutting cylinders C, E in the manner and for the purposes substantially as herein shown and described.

2. In bark mills, having the bed or beds on which the bark is placed concentrically adjustable in respect to the periphery of the cutting cylinder substantially as herein shown and described.

JOSEPH BRAKELEY.
